(57) **CLAIM**

The ornamental design for a putter, as shown and described.

DESCRIPTION

FIG. 1 is a top, right isometric view of a putter showing my new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is a top, right isometric view of a second embodiment thereof.

FIG. 9 is a front elevation view of FIG. 8.

FIG. 10 is a rear elevation view of FIG. 8.

FIG. 11 is a top plan view of FIG. 8.

FIG. 12 is a bottom plan view of FIG. 8.

FIG. 13 is a left side elevation view of FIG. 8; and,

FIG. 14 is a right side elevation view of FIG. 8.

The broken lines shown are included for the purpose of illustrating unclaimed subject matter and forms no part of the claimed design.

1 Claim, 8 Drawing Sheets
